(57) **CLAIM**

The ornamental design for a tire, as shown and described.

DESCRIPTION

FIG. 1 is a front right perspective view of a first embodiment of a tire showing our new design, the design repeated about the circumference of the tire, the dashed lines forming no part of the claimed design, the dash-dot boundary line delineating the area which forms no part of the claimed design;

FIG. 2 is a front elevation view thereof, the design repeated about the circumference of the tire, the dashed lines forming no part of the claimed design, the dash-dot boundary line delineating the area which forms no part of the claimed design;

FIG. 3 is a right elevation view thereof, the left elevation identical to the right elevation, the dashed lines for no part of the claimed design, the dash-dot boundary line delineating the area which forms no part of the claimed design;

FIG. 4 is a partial sectional view taken along line 4-4 in FIG. 2, the dashed lines forming no part of the claimed design; FIG. 5 is a front right perspective view of a second embodiment of a tire showing our new design, the design repeated about the circumference of the tire;

FIG. 6 is a front elevation view thereof, the design repeated about the circumference of the tire;

FIG. 7 is a right elevation view thereof, the left elevation identical to the right elevation; and,

FIG. 8 is a sectional view taken along line 8-8 in FIG. 6.
